UNITED STATES PATENT OFFICE

JAMES WILLIAM INGLETON, OF ASTORIA, OREGON

VAPORIZER FOR INTERNAL-COMBUSTION ENGINES

Application filed March 19, 1925. Serial No. 16,743.

The invention relates to new and useful improvements in devices whereby oils heavier than gasoline may be used in the running of a hydrocarbon engine.

An object of the invention is to provide a carburetor for hydrocarbon engines wherein the limit of the level of the oil in the supply chamber is below the intake port of the vaporizing chamber so that no oil is forced by gravity into the vaporizing chamber, and wherein the vaporizing chamber is so constructed that the exhaust gases may serve in an efficient manner to heat the vaporizing chamber.

These and other objects will in part be obvious and will in part be hereinafter more fully described.

In the drawings which show by way of illustration one embodiment of the invention—

Figure 1 is a side view of a combined apparatus embodying my improvements and showing the same as connected to both the intake manifold and the exhaust manifold;

Fig. 2 is a sectional view in a vertical plane centrally through the special carburetor for vaporizing and carbureting the heavy oil;

Fig. 3 is a sectional view on the line 3—3 of Fig. 2;

Fig. 4 is a vertical sectional view through the auxiliary tank for positively feeding the heavy oil to the gasifying chamber for speeding up the engine;

Fig. 5 is a modified form of discharge nozzle which may be used in the special vaporizing carburetor, and

Fig. 6 is a plan view of said nozzle.

The invention is directed broadly to a device which may be used for vaporizing and carbureting oils and the like. In order to carry out this invention, I have provided a special carburetor for vaporizing and carbureting the heavy oil. I prefer to use this, however, in conjunction with an ordinary standard carburetor for carbureting gasoline, the two being so assembled that gasoline may be used for starting the engine, after which the gasoline supply may be entirely cut off, if desired, and the engine operated by the vaporized and carbureted heavy oil. In other

words, my improved special carburetor can be very readily attached to the ordinary standard equipment of a hydrocarbon engine which is operated by gasoline. The special carburetor which I have devised includes a vaporizing chamber which may be made of any suitable metal, and which is preferably provided with a series of radiating vanes. This vaporizing chamber is placed in an outer chamber which is preferably surrounded with a suitable heat insulating material, and which is provided with a connection leading to the exhaust manifold, and a connection leading to the usual exhaust discharge, so that the exhaust gases from the engine passing through this outer chamber and in and about the vaporizing chamber located within the same, will quickly and thoroughly heat said vaporizing chamber. At the upper end of this vaporizing chamber there is a nozzle which extends through the outer wall of the outer chamber, and to a point adjacent a Venturi tube. Said Venturi tube is preferably located on the receiving end of the pipe which is connected to the intake manifold of the engine. Preferably, this special carburetor for the heavy oils is supported by the lower end of this intake pipe, and it is supported in such a way that it may be raised and lowered. This is particularly useful for installing the carburetor in an engine. It may also be utilized for shifting the position of the nozzle relative to the Venturi tube and thereby increasing or decreasing the suction of said Venturi tube on said nozzle. The oil is fed from a suitable supply to this vaporizing chamber. The main supply is controlled by a needle valve and will be drawn into the chamber as demanded by the engine. In other words, the engine drawing in air through the Venturi tube will lift the gasified oil from the vaporizing chamber and mix it with air and carry it to the intake manifold. By this arrangement, the gasifying chamber is under vacuum substantially all the time the engine is running, and this aids in the gasifying and the breaking up of the heavy oil.

Associated with this main feed of oil to the special vaporizing carburetor, is the

force feed which supplies oil particularly for speeding up the engine, and during the initial opening of the throttle valve, when the demand for fuel increases rapidly. To this end, I have provided an auxiliary tank which is connected by a suitable pipe to a supply port in the wall of the vaporizing chamber and at a point well above the needle valve controlled port. This auxiliary tank is provided with a piston and a rod connected to said piston and extending out of the upper end of the tank. The tank, of course, is closed, except for a supply pipe which enters the tank at the lower end thereof, and a discharge pipe which enters the tank at the upper end thereof and connects the same with a port in the wall of the vaporizing chamber. This piston is connected to the throttle valve located in the supply pipe just above the Venturi tube, and when said valve is open, the piston will be lifted. There is a bypass in the wall of this auxiliary tank which permits the oil to pass by gravity from the lower to the upper side of the piston when the piston is at a point near the bottom of the auxiliary tank, and at this time, the throttle valve is practically closed. This auxiliary tank is so set that the upper end thereof is below the level of oil in the main supply tank, so that when connected as above stated, so that the oil bypasses the piston, the tank will be filled with oil. The discharge opening, however, with which this auxiliary tank is connected, is above this oil level, so that there will be no escape of the oil therethrough, which might result in a siphoning action which would draw all of the oil out of the auxiliary tank. The special purpose of this auxiliary tank is to speed up the engine when varying the position of the throttle from a closed to an open position. As the piston is lifted, oil is forced thereby through the delivery port into the gasifying chamber, and as the oil is forced into this chamber and runs down the side wall thereof, it will be at once gasified. If the engine is at this time running on the heavy oil supply from the needle controlled port, then this will operate as an additional supply and prevent the stalling of the motor, and at the same time, gives a desirable pick up to the engine. Likewise, when passing from operating the engine on a gasoline supply, this additional oil feed may be utilized to keep the engine well under speed until the heavy oil is drawn in through the needle valve port by the suction of the engine. It will be understood, of course, that whenever the throttle is nearly closed for throttling down the engine, that the auxiliary tank will be replenished by the oil bypassing the piston, so that said auxiliary tank is kept supplied with oil to a sufficient amount to take care of all conditions above stated.

65. The invention will probably be better un-

derstood by a detail description of the apparatus which I have designed for carrying out the purposes stated.

Referring to Figure 1, I have indicated at 1 an ordinary carburetor. This has not been shown in detail, as it may be a carburetor of any standard type. The one which I have illustrated is provided with a throttle valve 2 and with the usual flange whereby the carburetor is attached to the intake manifold 3. It is understood that this carburetor is connected to a gasoline supply, and may be used in the ordinary way for starting an engine and for operating the engine, if desired. My invention, however, is primarily designed so as to provide means for vaporizing and carbureting a heavy oil which may be utilized for operating a hydrocarbon engine. To this end, the invention includes a special carburetor indicated at 4. This special carburetor may be attached to any engine equipped in the ordinary way with a carburetor operating with gasoline feed, merely by inserting a fitting 5 between the carburetor and the intake manifold, and providing said fitting with an intake pipe 6 in which is located a throttle valve 7. Said throttle valve 7 has an arm 8 attached thereto whereby it may be opened and closed. At the lower end of this intake pipe 6 there is a Venturi tube 9. Also attached to the lower end of this pipe is a flange 10, to which is attached my improved or special form of carburetor 4 by means of bolts 11, 11. This improved or special carburetor consists of an outer casing 12 which is preferably surrounded by heat insulating material 13 which is held against the outer wall of the casing by means of a sheet metal covering 14. Within the casing 12 there is a chamber 15. The main exhaust pipe 16 is connected to the wall 12 adjacent the upper end of this chamber, and a discharge exhaust pipe 17 is connected to the casing 12 at the opposite side and lower part of said chamber. Located within the chamber 15 is a metal vaporizing member 18. This vaporizing member 18 has a threaded connection with a supporting fitting 19 which is threaded into the wall 12 at the upper end of the chamber. This fitting 19 has an overhanging flange 20 against the under side of which a bracket 21 is clamped by means of a threaded collar 22. This bracket 21 is secured to the lower ends of the bolts 11. Said bolts are threaded into the bracket, and are held in adjusted positions therein by jamb nuts 23. The purpose of these threaded bolts is to permit the carburetor 4 to be raised and lowered during the installation of the carburetor on the engine. Also threaded into this central fitting 19 is a nozzle 24. This nozzle, of course, having a threaded connection with the fitting 19 can be readily detached and other nozzles substituted therefor, if desired, to meet the desired condition in the engine. The upper end of

the nozzle 24 extends into the throat 25 of the Venturi tube, and can be shifted into said tube to a greater or less extent, by raising and lowering the carburetor through the aid of the bolts 11. It will be understood, of course, that during the operation of the engine, when the throttle valve 7 is open, air will rush in through the Venturi tube and will create a vacuum at the discharge end of the nozzle 24, which in turn, through its suction on the nozzle, will create a vacuum in the nozzle and the chamber with which it is connected. This vaporizing member 18 referred to above, has a central vaporizing chamber 26. The fitting 19 has a passage 27 leading to this chamber 26 and connecting the chamber 26 with a passage 28 of the nozzle 24. Thus it is that the air rushing in through the Venturi tube will create a vacuum in the vaporizing chamber 26.

Attached to said carburetor is a main supply tank 29 which is mounted on a bracket 30. This main tank is connected to an oil supply 31 from which the heavy oil is fed to said tank by gravity, or any suitable means. This oil is an oil heavier than gasoline, and preferably is a heavy Deisel oil. The supply in the main tank is controlled by an ordinary float valve, so that the level in the main tank will be kept at a predetermined point which is below the ports leading into the vaporizing chamber 26 so as to prevent any possible chance of the oil in the main tank being siphoned out and into the vaporizing chamber and flooding the same. This main tank is connected to a pipe 32 which enters the chamber 15 and is coiled about in the same, and finally leads to an intake port 33 which is controlled by a needle valve 34. This needle valve 34 is mounted in a suitable supporting sleeve extending through the wall, of the carburetor where it is readily accessible for adjustment. It will be understood that the exhaust gases passing through the chamber 15 will not only heat the pipe 32 located therein, but will also heat the member 18 having the radiating vanes and containing the vaporizing chamber.

Associated with this main supply tank is an auxiliary tank 35, which may be attached to the main tank 29 or to the outer casing of the carburetor 4. This auxiliary tank is connected by means of a pipe 36 with the main supply tank 29. The auxiliary tank is equipped with a piston 37 attached to the lower end by a piston rod 38. This piston rod passes through a head 39 screwed into the upper end of the auxiliary tank, and said head is also provided with suitable packing to prevent any leakage by the piston rod. A pipe 40 leads from the upper end of the auxiliary tank or the cylinder containing this piston, into the chamber 15 and to an inlet port 41. This intake port 41 is located at some distance above the intake port 33 controlled by the needle valve, as shown in Fig.

2 of the drawings. The inner wall of the auxiliary tank 35 is provided with a vertical slot 42 which is longer than the depth of the piston, so that when the piston is at the lower end of the tank, oil may pass in through the pipe 36 and through the bypass 42 to the upper side of the piston, and thus fill the auxiliary tank. The upper end of the tank is slightly below the liquid level in the main tank 29, so that this auxiliary tank will be filled with the heavy oil. The inlet port 41, however, connected with the auxiliary tank, is well above the level of the oil therein, so that the oil cannot siphon out through this inlet port. The piston rod 38 is connected by the aid of suitable links and levers with the arm 8 controlling the throttle valve, as clearly shown in Fig. 1 of the drawings, so that when the throttle valve is open or closed, the piston will be raised or lowered in said auxiliary tank. The purpose of this auxiliary tank and the lifting of the piston is to force a suitable supply of oil through the upper intake port 41 into the vaporizing chamber. When the throttle valve is closed or nearly closed, the piston is at the lower end of the auxiliary tank, and the oil may bypass to the upper side of the piston. When, however, the piston has been raised to the position shown in Fig. 4, then the bypass is closed, and only the oil above the piston can be forced over into the vaporizing chamber.

In the operating of an engine equipped with my improved vaporizing and carbureting devices, the engine is preferably started by the use of the gasoline and through the opening of the throttle valve of the carburetor 1. At this time, the throttle valve of the carburetor 4 for the heavy oil is closed. As soon as the engine is under way, the exhaust gases will pass into the chamber 15 and thoroughly heat up all the interior parts of the carburetor 4. This includes the oil pipes extending into the same, and particularly the vaporizing member 18 containing the vaporizing chamber 26. When the engine is well warmed up, then the throttle valve 7 may be opened so that the engine may be supplied with the gasified heavy oil. The opening of this valve 7 results in the lifting of the piston 37 in the auxiliary tank, which in turn will force a certain amount of the oil from the auxiliary tank through the inlet port 41. This oil passing into the vaporizing chamber will be at once entirely vaporized or gasified. At the same time, when the throttle valve is open and the oil forcibly fed into the gasifying chamber, air will pass through the Venturi tube and the pipe 6 into the intake manifold. This in-rushing air will create a vacuum which will suck the vaporized oil from the vaporizing chamber 26 through the discharge nozzle 24 and the vaporized oil will mix with the air and enter the intake mani-

fold where it will operate the engine in the usual way. Of course, only a small amount of oil is forcibly fed to the gasifying chamber, and this is primarily for speeding up the engine and creating a proper suction to draw the oil in through the needle controlled port 33. At the same time, the engine may be supplied with the gasified gasoline and operated in conjunction therewith, if so desired. In other words, the carburetor for the gasoline is entirely independent from the carburetor for the heavier oil and may be used simultaneously therewith, or in part therewith, as is desired. When the suction is sufficient, the heavier oil will be drawn in through the intake port 33 controlled by the needle valve, as above stated, and as the oil comes in through this intake port into the vaporizing chamber 26, it will be at once gasified. Inasmuch as this chamber is continuously under a vacuum through the suction in the Venturi tube, the incoming heavy oil will be quickly vaporized and thoroughly broken up, and be entirely in a gasified form. In other words, the chamber 26 does not fill with the heavy oil which rises and overflows through the nozzle 24. It is lifted out of the vaporizing chamber in the gasified form, as just stated. When the throttle valve is opened to increase the fuel fed to the engine, the amount of oil in the mixture will be comparatively lean, except for the fact that the opening of the throttle valve simultaneously forces more oil into the gasifying chamber, and this supplies the extra demand to thoroughly gasify and enrich the extra air coming in through the Venturi tube.

It will be noted that the inner member 18 with its radiating vanes extends substantially across the entire width of the chamber 15 so that the exhaust gases from the engine will necessarily come in contact therewith and the radiating vanes formed thereon.

It will also be noted that the heavy oil is drawn through the intake port 33 by the vacuum created in the vaporizing chamber 26. This vacuum is in turn created by the air passing through the Venturi tube into the intake manifold, and this in turn is controlled, of course, by the demand of the engine. Therefore, the amount of heavy oil supplied to the vaporizing chamber is in small increments determined by the need of the engine, and as this small portion of oil enters the vaporizing chamber, it will be at once vaporized. Of course, if the engine increases in speed, the demand will increase, and more oil will be drawn in. In other words, the vaporizing chamber 26 is subject to the suction of the engine at all times, so that no unvaporized oil can accumulate therein.

In Figures 5 and 6, I have shown a slightly modified form of nozzle which may be substituted for the nozzle 24 shown in Fig.

2. This nozzle consists of a body portion 42' which is provided with a thread whereby it may be screwed into the fitting 20. This body portion has a projecting nozzle 43 which is somewhat larger in diameter than the nozzle 24. Extending through the nozzle and body portion thereof are ports 44' through which the vaporized oil passes. This nozzle is also provided with radial grooves 45. I have shown eight of these radial grooves, although the number may be varied to suit the conditions and results sought to be obtained. These radial grooves open at the side of the nozzle and the end of the nozzle, and the bottom of the groove is curved as indicated by the broken line 46 in Fig. 5. The purpose of these grooves is to take in air, and by arranging the grooves as described, the air will be directed to the center of the multiple jets passing through the ports 44'. This intermixing of the air and the vaporized oil will greatly aid in the forming of a combustible mixture. It is understood that the air does not in any way mix with the vaporized oil until the oil leaves the nozzle, but it is thoroughly intermixed with the various jets as they come out of the nozzle. Of course, the air is caused to pass through these radial grooves by the suction of the engine, and the air is taken into the throat of the Venturi tube which operates to thoroughly mix the air with the vaporized oil.

It is obvious that changes may be made in the arrangement of the devices selected and also in the details of the vaporizing means for the heavy oil without departing from the spirit of the invention as set forth in the appended claims.

Having thus described the invention, what I claim as new and desire to secure by Letters-Patent, is—

1. A carburetor comprising a casing forming an outer chamber, a vertically disposed member located within said outer chamber and having a vaporizing chamber formed therein, means for passing the exhaust gases from a hydrocarbon engine through said outer chamber for heating the vaporizing chamber, a supply tank associated with said casing, a pipe leading from the supply into the outer chamber and in a circuitous path in said chamber to an intake port formed in the wall of the member located in the casing for feeding oil to the vaporizing chamber, a needle valve for controlling said intake port, said intake port being disposed at an elevation above the surface of the oil in the supply tank whereby the oil is drawn from the tank into the vaporizing chamber by the suction force of the engine, said member containing the vaporizing chamber being circular in cross section and having horizontally projecting ribs, said ribs extending from one side of the casing to the other, the intake for the exhaust gases being at one side of said

member and the outlet at the other whereby the exhaust gases pass between the ribs for heating said member.

2. A carburetor comprising a casing having an outer chamber, a vertically disposed member located in said casing and having a vaporizing chamber therein, means attached to the casing for suspending said member in said casing, an intake port in said member leading to the vaporizing chamber for delivering oil to said chamber, a supply chamber, a pipe connected with said supply chamber and passing through said casing into and in a circuitous path about said outer chamber and connected with said intake port, a nozzle connected to said member, and a Venturi tube associated with said nozzle and the intake manifold of a hydrocarbon engine, said intake port being disposed above the level of the oil in the supply chamber whereby oil is drawn from said supply into the vaporizing chamber vaporized and mixed with air and supplied to the intake manifold of the hydrocarbon engine by the suction of the engine, and means for passing the exhaust gases into and out of said chamber for heating the member containing the vaporizing chamber.

In testimony whereof, I affix my signature.
